By Henry J. Bevington, Attorney.

UNITED STATES PATENT OFFICE.

FRANK J. COLMUS, OF BALTIMORE, MARYLAND.

HITCH-PIN FOR PIANOS AND OTHER STRING INSTRUMENTS.

1,339,689.

Specification of Letters Patent. Patented May 11, 1920.

Application filed January 17, 1920. Serial No. 352,030.

To all whom it may concern:

Be it known that I, FRANK J. COLMUS, a citizen of the United States, residing at Baltimore city, State of Maryland, have invented certain new and useful Improvements in Hitch-Pins for Pianos and other String Instruments, of which the following is a specification.

This invention relates to devices for securing one end of the strings of pianos and similar musical instruments, the same consisting of pins around which the strings are looped or anchored in any other approved manner, and the invention has for its object to provide a novel and improved pin by the use of which the instrument can be more readily strung, as will be pointed out hereinafter.

In order that the invention may be better understood, reference is had to the accompanying drawing forming a part of this specification, and in said drawing—

Figure 1 is a plan view showing the application of the invention; Fig. 2 is a section on the line 2—2 of Fig. 1; Fig. 3 is an enlarged elevation of one of the pins, and Fig. 4 is an elevation showing a slightly modified pin.

Referring specifically to the drawing, 5 denotes a fragment of some of the strings 30 of a piano or similar instrument, the same being secured to the hitch pins 6 by being looped around the same, or in any other suitable manner. The pins 6 are not sharp 35 at one end and they are not driven into the pin plank 7, but the latter has holes 8 into which the pins are inserted. The pins are set slanting as usual.

Ordinary hitch pins are sharp at one end 40 so that they may be driven into the pin plank 7, which is an operation involving the expenditure of much time and labor, as they must be accurately driven to project the proper distance from the plank. The 45 pins are also difficult to remove if they

should happen to break off, which is a frequent occurrence. In order to overcome this objection, a hitch pin has been devised which can be easily set in place and readily removed if its projecting end should break 50 off. This object is attained by providing the pin plank 7 with the holes 8 to seat the pins. The pins fit in these holes sufficiently tight to prevent dropping out, but not so tight as to prevent ready removal if necessary. 55 The pins are also blunt at both ends, and both ends are alike. Intermediate its ends, the pin has an abutment. Fig. 3 shows this abutment to be two tongues 9 punched out of the body of the pin and bent 60 outwardly therefrom. In Fig. 4 the body of the pin has an annular shoulder 10 encircling the same, this shoulder serving as the abutment. In both instances the abutment is just midway between the ends of 65 the pin, and the ends of the pin are alike. The pins can therefore be inserted into the holes 8 with either end entering the same, and it is not necessary for the workman to waste any time looking at the pins and selecting the end to be inserted. The abutments serve as stops to limit the distance 70 the pins are to enter the holes, and hence they all project the proper distance from the pin plank 7.

It will be evident from the foregoing that the invention provides a very simple and efficient expedient for facilitating the stringing of pianos and similar musical instruments.

I claim:

The combination with a pin plank having holes; of hitch pins adapted to seat in said holes, said pins having both of their ends rounded and alike, and having abutments intermediate their ends to limit the extent of insertion into the holes.

In testimony whereof I affix my signature.

FRANK J. COLMUS.
